COMBINED MIXER AND DISPENSER

Maxwell Bentley, 1331 Newbridge Road,
North Bellmore Village, N.Y. 11710

Filed Apr. 4, 1967, Ser. No. 6,510

Term of patent 14 years

(Cl. D44—1)

FIG. 1 is a side elevational view of a combined mixer and dispenser embodying my new design;

FIG. 2 is a top plan view thereof;

FIG. 3 is a bottom plan view thereof;

FIG. 4 is a front elevational view thereof; and

FIG. 5 is a rear elevational view thereof.

The characteristic feature of the design resides in the combination of the particular configuration and arrangement of the upper opaque portion with a transparent lower portion, each of said portions being substantially concave and having a proportioned relationship therebetween of approximately 1 to 2.

I claim:

The ornamental design for a combined mixer and dispenser, as shown and described.
